UNITED STATES PATENT OFFICE.

GEORGE C. THIESEN, OF JERSEY CITY, NEW JERSEY.

DESIGN FOR A PLATE OR SIMILAR ARTICLE.

SPECIFICATION forming part of Design No. 36,260, dated March 31, 1903.

Application filed February 20, 1903. Serial No. 144,343. Term of patent 3½ years.

To all whom it may concern:

Be it known that I, GEORGE C. THIESEN, a citizen of the United States, residing at Jersey City, Hudson county, State of New Jersey, have invented and produced a new, original, and ornamental Design for Plates or Similar Articles, of which the following is a specification, reference being had to the accompanying drawings, forming a part thereof.

Figure 1 is a plan view of a plate, showing my new design; and Fig. 2 is a longitudinal section thereof.

As shown in the drawings, the leading or material feature of my design consists of a leafy effect and a representation of a lobster, both upon an approximately circular shallow surface. The leafy effect is produced by a number of representations *a* of lettuce-leaves, which are ribbed and fluted for representing veins and to represent the wrinkles, creases, or folds of the natural leaf. The representation *b* of a lobster is spread upon the leaves

a, which are upon the entire upper surface of the plate or saucer, the representation of the lobster being so disposed at one side of the plate or saucer that the edge thereof juts out at the edge of the plate or saucer, and one of the claws does likewise.

The rim *c* of the dish has the irregular wavy outline of the edges of the leaves.

Having thus described my invention, what I claim as new, and desire to secure by Letters Patent, is—

The ornamental design for a plate or similar article, substantially as shown and described.

In testimony whereof I have signed this specification in the presence of two subscribing witnesses.

GEORGE C. THIESEN.
